UNITED STATES PATENT OFFICE.

CHARLES B. ROBERTS, OF MODESTO, CALIFORNIA.

SCRAPER.

1,098,640.

Specification of Letters Patent.

Patented June 2, 1914.

Application filed August 2, 1913. Serial No. 782,666.

To all whom it may concern:

Be it known that I, CHARLES B. ROBERTS, a citizen of the United States, residing at Modesto, in the county of Stanislaus, State 5 of California, have invented certain new and useful Improvements in Scrapers; and I do declare the following to be a clear, full, and exact description of the same, such as will enable others skilled in the art to 10 which it appertains to make and use the same, reference being had to the accompanying drawings, and to the characters of reference marked thereon, which form a part of this application.

15 This invention relates to improvements in scrapers and is particularly designed as a wheel scraper, the object of the invention being to produce a wheel scraper in which the wheels are adapted both to carry the 20 load when the scraper is full and also to act as a substitute for runners now commonly used when the scraper is being emptied.

25 A further object is to produce an easy and effective means for raising the scraper from scraping position onto the wheels when it is loaded and simultaneously closing the front of the scraper to prevent the dirt from falling out.

30 The invention then further embodies a quick and effective means for throwing the scraper into dumping position and then returning all of the parts to normal carrying or loading position as may be desired.

35 A still further object of the invention is to produce, in conjunction with the above mechanism, suitable adjustments for preventing the scraper from tipping too far or becoming hard to handle and further to adjust it so as to spread the dirt thick or thin or in one heap or pile as may be desired.

40 A further object of the invention is to produce a simple and inexpensive device and yet one which will be exceedingly effective for the purposes for which it is designed.

45 These objects, I accomplish by means of such structure and relative arrangement of the parts as will fully appear by a perusal 50 of the following specification and claims.

On the drawings, similar characters of reference indicate corresponding parts in the several views.

55 Figure 1 is a side elevation of the scraper as it appears in carrying position. Fig. 2 is a similar view as it appears in loading po-

sition. Fig. 3 is a similar view as it appears in dumping position. Fig. 4 is a top plan view of the scraper.

Referring now more particularly to the characters of reference on the drawings, I first provide two carrying arms 1 provided with upwardly extending portions 2. In the outer ends of the arms 1, as at 3, are normally carried turnable wheels 4. Just 60 back of the points at which the arms 1 carry the wheels 4, I pivotally mount a scraper 5 on said arms 1 as at 6.

65 Flexibly connected with the sides of the bowl 5, below the pivotal point 6, are draw 70 bars 7 projecting a distance beyond the front of the bowl and rigidly joined at their outer ends by means of a cross beam 8. The member 8 is provided with a central downwardly projecting supporting member 75 9 having a runner shoe 10 on its lower end. Projecting upwardly from each draw bar 7 is a stop frame or arm 11 for the purpose as will appear.

75 Pivottally mounted to each side of the bowl 5 above the pivotal point 6, as at 12, is an arm 13, such arms having a cross bar 14 carrying a closing door blade 15, capable, when the arms 13 move on their pivotal points 12, to drop down over the front of 80 the bowl 5 to form a closing door for the same when it is in carrying position as shown in Fig. 1. When in loading position as shown in Fig. 2, this door 15 is held normally open by means of a chain 16 connect-

90 ed from the member 14 to a cross member 17 on the members 2. Said member 17 is provided with an operating lever 18. As will be noted when the scraper is in loading position as shown in Fig. 2, the wheels 4 are held clear of the ground by means of the arms 1 and 2 being in their normal backward position. Then when the scraper is 95 loaded and is to be carried, the lever 18 is operated to move the arms 1 and 2 on the pivotal point 6 which brings the wheels 4 against the ground and then by continuing the movement of the lever 18, this will lift the bowl clear of the ground and cause it to be suspended and carried on the wheels 100 4 and shoe 10 as shown in Fig. 1. This same action of course loosens the chain 16 to permit the arms 13 to drop down to cause the door 15 to close in front of the bowl to prevent the dirt from falling out. The arms 1 105

110 and 2 are also brought to a stationary fixed position to hold the bowl 5 suspended to

ride on the wheels 4 by means of the member 17 coming in contact with the stop members 11. After the bowl is loaded and carried to the point desired as above set forth 5 and it is desired to empty the same, a lever 19 on the back side of the bowl is operated to swing the bowl on its pivotal connections with the arms 1 to tip the said bowl to inverted position as shown in Fig. 3. When 10 this action takes place, the cross member 14 rests against the member 7 and is prevented from moving with the bowl for this reason, hence, the said door 15 is opened away from the end of the bowl to permit the dirt to 15 be emptied therefrom.

Pivottally mounted on the rear of the bowl 5 is a latch member 20. When the bowl is tilted to emptying position as shown, this latch member is thrown over and engages 20 the member 17 as it rests on the members 11. Then when the bowl is pulled back to carrying position again, this latch also brings back the member 17 carrying the arms 1 and 2 and incidentally the wheels 4 into 25 the position shown in Fig. 2 and by means of the chain connection 16 the member 14 carrying the door 15 is also brought back to open position leaving the scraper ready to be filled again. The latch 20 when engaging 30 the bar 17 of course locks the bowl 5 in the position in which it is dumped so that it cannot tilt forward or backward until brought back in the manner desired. Also by making the latch 20 adjustable the 35 angle at which the bowl is held tilted in dumping position could be varied to spread the dirt in a thick or thin layer or pile as might be desired.

At the rear ends of the upper edges of 40 the sides of the bowl, I provide stop members 21 and at the lower ends of the front edges of the sides of the bowl, I provide stop members 22. These stop members, by striking the members 7 limit the tilting 45 movement of the bowl forward or backward respectively.

From the foregoing description it will readily appear that my improved scraper embodies the following features, namely, a 50 scraper bowl, means for quickly and easily raising the bowl onto carrier wheels when loaded and closing the front of the scraper to hold the dirt therein, means for quickly

tilting the bowl to emptying position and simultaneously opening the door and further a means for returning all of the parts to normal loading position again. From the foregoing description it will be readily seen that I have produced such a device as substantially fulfills the objects of the invention 60 as set forth herein.

While this specification sets forth in detail the present and preferred construction of the device, still in practice, such deviations from such detail may be resorted to 65 as do not form a departure from the spirit of the invention.

Having thus described my invention what I claim as new and useful and desire to secure by Letters Patent is:

A device of the character described comprising a scraper bowl, a pair of arms pivotally mounted on said scraper bowl and carrying wheels on their forward ends and a cross bar on their rear ends, draw bars 75 pivotally mounted in said scraper bowl and being supported at their outer ends, an upwardly projecting stop member on said draw bars, means for moving said arms on their pivotal points to cause said cross bar 80 to engage said stop member and to cause said wheels to engage the ground surface whereby said scraper bowl will be held suspended between said arms, a closure held normally away from the front of said 85 scraper bowl but adapted to move in front thereof when the same is so suspended between said arms, means for tilting said scraper bowl on its pivotal connection with said arms to throw it to inverted emptying 90 position, said closure engaging and being held from further movement by said draw bars when said bowl is so tilted to said inverted position, a chain connecting said cross bar and said closure, and a latch pivotally mounted on said bowl and adapted 95 to engage said cross bar when said bowl is moved to said inverted position, as described.

In testimony whereof I affix my signature 100 in presence of two witnesses.

CHARLES B. ROBERTS.
